UNITED STATES PATENT OFFICE.

FREDERICK G. PHELPS, OF NEW YORK, N. Y.

SELF-CONFORMING STRAW HAT.

Application filed November 10, 1924. Serial No. 748,844.

The present invention relates broadly to hats and more especially to a straw hat adapted to be self-conforming to the head of the wearer.

5 Heretofore in the art, flexibility in stiff straw hats has been obtained in two general ways. One way has been to manufacture the crown and brim of the hat of stiff straw, such as sennit straw, and in the zone comprising the conjuncture between the brim and the crown, the side wall of the crown of the hat has been made of straw which in itself is flexible per se, that is, a different character of straw, such as milan straw braid, is used in this zone; or the straw may be of the same quality as the brim and crown excepting that it is of smaller size to obtain a finer weave, which weave of itself is more flexible than the wall of the crown or the 10 brim. Flexibility is obtained in this prior art type of hat by considerable additional expense. In making these prior art hats, the operator must stop and choose braids of different types to sew together to make up 15 the hats and must either adjust the sewing mechanism to operate upon the different kinds of braids; or where entirely distinctive types of braids (such as the ordinary sennit braid is used for the crown and milan 20 braid is used for the head zone) different machines must be used for the sewing. This adds to the cost and slows up manufacture.

Another type of stiff hats with flexible head zones has long been known in the art 35 by making the entire head of one kind of braid, such as sennit braid, and then leaving the portion adjacent the conjuncture of the crown and the brim, i. e., the head contact zone, substantially free from glue or stiffening material.

40 The difficulty with both of these prior art structures is that such a hat is lacking in supporting strength against forces applied downwardly to the crown. Such forces tend to cause a telescoping action or deforming action in the flexible zone area, because of the lack of resistance against vertical forces applied on the crown. Furthermore, such prior art hats tend to lose their shape 45 in the flexible area, and even though this area is partly covered by the hat ribbon or band, the deforming effect spreads to the side wall of the crown and the hat loses its trim appearance.

50 55 The present invention comprises an improvement upon the latter type prior art

hats in which the hat is formed of a single kind of straw braid, and with the head bearing zone unstiffened by glue or the like. In the present invention, the strength of the 60 vertical wall of the crown is obtained by an additional member which gives the necessary strength in a vertical direction without decreasing the flexibility of the vertical wall in a lateral direction. This additional 65 member may be a band of plaited straw which permits of limited circumferential expansion in the flexible zone. The present invention thereby combines the advantages both in economy and structure of the unstiffened unitary kind of straw braid type 70 hat and overcomes the faults of this type of hat as constructed in the past.

75 My invention may be carried out in many ways, but preferably is carried out by making the entire hat of one type of braid and introducing a supporting member over the area of flexibility at the head contacting zone; then stiffening by suitable material, the crown and the brim except the zone 80 which is to be flexible. In the preferred form, this stiffening member comprises a single wide braid of straw which is sewed as a cylindrical band on the inside of the hat and over the zone of flexibility so that 85 the lower edge of the braid extends out slightly over the side of the stiff flat brim and the upper edge of this supporting braid extends over and is secured to the stiffened side wall of the crown of the hat. Where 90 this supporting braid is on the inside of the hat it not only has the advantage of permitting all of the lateral flexibility and supporting the crown side wall against telescoping or lengthwise forces, but it also covers 95 the tips or edges of the straw braid adjacent the head contacting zone and leaves a very smooth surface to support the inside leather or sweat band thereby making a comfortable hat. Furthermore, this reenforcing braid 100 permits the use of a lesser total amount of glue or stiffening means per hat, thereby insuring an economy in this particular. This type of hat is extremely flexible and easy on the head, and produces a smooth head bearing surface which cannot be obtained where the interior surface of the head bearing zone comprises the edges of a plurality of rows of braids sewed together, as has been the prior art custom.

105 110 In view of the foregoing, the principal object of the present invention is a self-con-

forming stiff straw hat in which the hat is preferably formed of a single type of straw and in which a flexible zone is provided adjacent the juncture of the brim and the crown; which zone is reenforced to sustain the side wall of the crown without destroying the lateral flexibility of the head conforming zone.

Another object of the present invention is 10 a straw hat in which the head conforming zone is flexible, with a portion of the crown side walls stiffened and with a supporting member extending from the stiffened side wall over the flexible zone.

15 A still further object of the present invention is a straw hat in which the head conforming zone is covered with a single wide braid of small straw.

Another object of the present invention is 20 a straw hat in which the lower side wall of the crown and the inner portion of the brim are flexible and with a smooth circular band of single straw braid constructed to extend over the flexible portion of the brim and 25 over the flexible portion of the crown.

Other and further objects of the present invention will in part be obvious and will in part be pointed out hereinafter in the specification following by reference to the accompanying drawings forming a part of this 30 application.

Fig. 1 of the drawings illustrates a hat embodying the preferred form of the present invention with a portion of the hat broken 35 away to better illustrate the construction.

Fig. 2 is a sectional view through a portion of the head contacting zone and illustrates the preferred way of arranging and securing a flexible straw braid on the hat 40 according to my invention.

Fig. 3 is a sectional view similar to Fig. 2 in which the sweat band and ribbon are shown in place.

45 Referring now more especially to the drawings, the hat preferably comprises a crown portion 1 and a brim portion 2, both of which may be formed of a single type of straw braid, or if desired, various types may be utilized for purposes of ornamentation or 50 ventilation.

The crown 1 of the hat is preferably stiffened to a point substantially adjacent the arrow A in the figures and the brim 2 is stiffened to a point adjacent the arrow 55 B. The head conforming zone between the arrows A and B is unstiffened except for such slight amount of stiffening glue as may accidentally work into this portion during the fabrication of the hat. In the stiffening 60 operation, the hat is preferably immersed in a stiffening bath through a floating board provided with an opening through which the crown of the hat may be extended. This leaves a portion of the crown 65 adjacent the brim unimmersed in the stiffen-

ing solution. The brim is stiffened by being passed through a slot in a suitable floating board so that while the edge of the hat is immersed in the solution, a narrow zone adjacent the crown is not immersed. The glue 70 cements the over lapping braids together where they are sewed and so when the glue is dried this glued portion of the hat is not only stiffened but the rows of braid are actually glued together to present a substantially continuous side wall. Now in the narrow unglued zone the braids are held together only by the sewing threads and the braids are therefore more or less free to move relatively to each other thereby securing flexibility but this zone is weak unless properly reenforced.

A single wide supporting braid 4 is sewed to the hat over the unstiffened zone between the arrows A and B, with the upper edge 85 of this single braid extending substantially to the stiff side wall of the crown and the lower edge of this single width straw braid is preferably sewed to the brim at substantially the inner limit of the stiffened portion thereof. This single width strip of braid, or the like is preferably formed of narrow flat straws which provide a very smooth surface that covers the rough inner edges of rows 5 of straw braid from which the hat is made and also provide a braid of considerable strength against crushing forces applied to the edges of the braid.

The hat is self-conforming, not only in the sense that it can readily change shape 100 to conform to the shape of the wearer's head, but also in the sense that it can undergo a certain amount of circumferential expansion to conform to the size of the wearer's head. It will be noted that the band of straw 4 is so plaited that the strips of straw lie at an angle to a horizontal plane passing through the crown of the hat, and hence this band may slightly expand circumferentially or lengthen in much the same manner as a strip of cloth cut on the bias. This circumferential expansibility of the band 4 is not interfered with by the stitching 105 at the edges of the band. The expansion will take place primarily in a zone just 110 above the bottom of the crown, e. g. in the vicinity of the lower leader for numeral 4 in Fig. 2; and expansion in such a zone does not necessitate an increase in the total length of the rows of stitching at the edges of the band 4. However, the rows of stitching are themselves somewhat expansible.

The thread in the rows of stitching lies in a configuration such as would be obtained by placing a series of numeral 8's end to end; and the material in the loops of thread is yielding enough to permit the loops to collapse slightly and let the rows of stitching lengthen after the manner of lazy tongs. Also the thread of the stitching is itself 130

stretchable to a slight extent. This construction produces a very comfortable hat to wear, without substantial cost to manufacture.

5 After the hat is completed and blocked, the sweat band 6 is sewed in position over the smooth wide braid 5, in the usual manner of attaching sweat bands and the ribbon 7 is attached to the outside of the crown portion of the hat in accordance with well known practice. The straw which is visible from the upper portion of the hat preferably is of one character and weave instead of different types of weaves which are essential to the old type hats referred to in connection with the prior art, however, I do not limit the present invention to a single type straw hat, because various types and kinds of straw may be used for ornamentation or ventilation without departing from the scope of this invention.

Having thus described my invention, what I claim is:—

1. As an article of manufacture, a straw hat having a stiffened crown portion, a stiffened brim, and a flexible zone comprising the conjuncture of the crown and the brim, in combination with a single wide braid of straw extending circumferentially of the hat and overlying the flexible zone, said braid being attached to the inside of the crown and to the bottom of the brim to provide a vertical support for the flexible side wall of said crown.
2. As an article of manufacture, a straw hat comprising crown and brim portions formed from overlapping rows of straw braid sewed together, the braid being of the same type throughout the crown and brim portions, a straw under brim sewed to said brim portion, the hat having an unstiffened zone which includes the conjuncture of the brim and crown and the remainder of the brim and crown being impregnated with stiffening material, and a flexible smooth band of fine plaited straw having one edge sewed to the stiffened portion of the under brim and the other edge sewed to the stiffened portion of the crown, the band extending from the lower side of the brim upwardly within the crown to strengthen and reenforce the unstiffened zone of the hat.
3. As an article of manufacture, a straw hat comprising crown and brim portions formed from overlapping rows of straw braid sewed together, the braid being of the same type throughout the crown and brim portions, the hat having an unstiffened zone which includes the conjuncture of the brim and crown and the remainder of the brim and crown being impregnated with stiffening material, and a flexible smooth band of

fine plaited straw having one edge sewed to the stiffened portion of the brim and the other edge sewed to the stiffened portion of the crown, the band extending from the lower side of the brim upwardly within the crown to strengthen and reenforce the unstiffened zone of the hat.

4. A straw hat made from one type of braid throughout the brim and crown and comprising an unstiffened zone which includes the conjuncture of the brim and crown, the remainder of the brim and crown being impregnated with stiffening material; and a smooth band of fine plaited straw extending over the unstiffened zone, said band being attached to the stiffened portion of the brim and to the stiffened portion of the crown.

5. A straw hat made from one type of braid throughout the brim and crown and comprising an unstiffened zone which includes the conjuncture of the brim and crown, the remainder of the brim and crown being impregnated with stiffening material, and a smooth reenforcing band extending over the unstiffened zone on the interior of the hat, said band being capable of circumferential expansion and being attached to the stiffened portion of the brim and to the stiffened portion of the crown.

6. As an article of manufacture; a straw hat having brim and crown portions impregnated with stiffening material, the stiffened brim and crown portions being separated by an unstiffened zone which includes the conjuncture of the brim and crown; and a flexible smooth band of soft material having one edge attached to the stiffened portion of the brim and the other edge attached to the stiffened portion of the crown, said band extending from the lower side of the brim upwardly within the crown to strengthen and reenforce the unstiffened zone of the hat.

7. As an article of manufacture; a straw hat having brim and crown portions impregnated with stiffening material, the stiffened brim and crown portions being separated by an unstiffened zone which includes the conjuncture of the brim and crown; and a flexible smooth band of soft material having one edge attached to the stiffened portion of the brim and the other edge attached to the stiffened portion of the crown, said band extending from the lower side of the brim upwardly within the crown to strengthen and reenforce the unstiffened zone of the hat, the portion of said band which overlies the conjuncture of the brim and crown being unsecured to the hat.

FREDERICK G. PHELPS.
